ATTORNEY

UNITED STATES PATENT OFFICE

FREDERICK SCHWEIGERT, OF NEW YORK, N. Y.

PLIERS

Application filed May 8, 1929. Serial No. 361,454.

This invention relates to new and useful improvements in pliers.

The invention has for an object the provision of a device of the class mentioned which is of simple durable construction, dependable in use and efficient in action, and which may be manufactured and sold at a reasonable cost.

The invention proposes the use of detachable biting pieces for plier jaws arranged to be quickly and firmly adjusted and held in place upon a plier so as to be exchangeable on the jaws of various pliers, which is of extreme advantage in that new attachments may be engaged on pliers to take the place of worn and damaged ones.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Figs. 1 to 4 inclusive are side elevational views of pliers constructed according to various designs and embodying the features of this invention.

Fig. 5 is an end elevational view of any of the pliers shown in the previous figures, for example looking in the direction of the arrows 5—5 of Fig. 1.

Fig. 6 is a view similar to Fig. 5 but illustrating a modification.

Fig. 7 is a fragmentary side elevational view of a plier constructed according to another embodiment of the invention.

Fig. 8 is a vertical sectional view taken on the line 8—8 of Fig. 7.

Fig. 9 is a view similar to Fig. 7, but showing the extreme opened position of the pliers, and the view being partially in section.

The reference numerals 10 indicate generally the jaws of a plier, which jaws are pivotally connected as at 11 and provided with rear handles 12 extending to the rear of the pivot point 11. Biting pieces 13 are mounted on the inner opposite engaging

faces of the jaws 10. For facilitating this connection the jaws 10 are preferably formed with dove-tail tongues 14 slidably engaging in dovetail grooves formed in the biting pieces 13. Rivets 15 are engaged thru the biting pieces and the tongues 14 for holding the biting pieces in place.

In Figs. 2, 3 and 4, pliers have been shown of various designs. Each of these pliers have jaws pivotally connected and provided with rear handles. One of the jaws of each of the pliers is provided with a pintle rivet 16 which engages in an elongated slot 17 formed in the other of the jaws. The slot 17 is provided with enlarged end portions as shown in the drawing so as to provide a pivoting of the jaws with the rivet 16 disposed in one or the other ends of the slot, the rivet being formed with flat sides permitting movement of the jaws to one or the other of the latter positions. This construction is customary in present day pliers.

In Fig. 2, the plier jaws are indicated by reference numeral 10^a and the handles by 12^a. Biting pieces 13^a are shown attached upon the jaws by rivets 15^a. In Fig. 3 the jaws are indicated by numerals 10^b, the handles by 12^b, the biting pieces by 13^b and the rivets by 15^b. In Fig. 4 the jaws are indicated by numerals 10^c, the handles by 12^c, the biting pieces by 13^c and the rivets by 15^c.

In the modified form of the device illustrated in Fig. 6, the biting pieces 13' are shown connected with the jaws 10' by tongues integral with the jaws and engaging in grooves formed in the biting pieces. These tongues have necks 18 and end portions 19. In the previous forms the tongue and groove connections were of dovetail form.

In the modified form of the device illustrated in Figs. 7 and 8, the plier jaws 10^d are formed with cavities 20 in which levers 21 are pivotally mounted intermediate of their ends. The front ends 22 of these levers are turned at right angles to the main portions and normally engage in apertures 23 formed in the biting pieces 13^d for holding these biting pieces against slidably disengagement. Springs 24 are coaxially

mounted upon the pivot points of the levers and urge the ends 22 into the said engaged positions. The other ends of the levers 21 are formed with inclined rear faces 25, and 5 pins with enlarged heads 26 rest against the inclined faces 25 and are disposed in slots 27 formed in the jaws 10^d. When the pliers are open to the very limit to which they may be opened the handles 12^a act against the 10 pins 26 for forcing them frontwards in the slots 27 and forcing one of the ends of the levers 21 inwards for forcing the other ends outwards so that the ends 22 disengage from the apertures 23 and permit the removal of 15 the biting pieces 13^d.

In operation of the various designs shown, the pliers may be used in customary fashion. When the biting pieces become worn, damaged or broken they may be removed and 20 replaced by new ones. In the form of the invention shown in Figs. 1 to 6 inclusive it is necessary to remove the rivets to permit a removal of the biting pieces. In the form shown in Figs. 7 and 8, the handles may be 25 opened to an extreme position for moving the front ends 22 of the levers, which permits a disengagement of the biting pieces.

While I have shown and described the preferred embodiment of my invention, it is 30 to be understood that I do not limit myself to the precise construction herein disclosed and the right is reserved to all changes and modifications coming within the scope of the invention as defined in the appended claims.

35 Having thus described my invention, what I claim as new, and desire to secure by United States Letters Patent is:—

1. A pair of pliers, comprising pivoted jaws, handles connected with the jaws and 40 extending to the rear of the pivot point, biting pieces with tongues engaging in grooves formed in the jaws, and means for holding the biting pieces in place, comprising pivoted levers mounted in the jaws and engaging 45 in apertures in the biting pieces, and means for disengaging the levers when the jaws are fully opened.

2. A pair of pliers, comprising pivoted jaws, handles connected with the jaws and 50 extending to the rear of the pivot point, biting pieces with tongues engaging in grooves formed in the jaws, and means for holding the biting pieces in place, comprising pivoted levers mounted in the jaws and engaging 55 in apertures in the biting pieces, and means for disengaging the levers when the jaws are fully opened, said latter means including pins engageable by the handles.

3. A pair of pliers, comprising pivoted 60 jaws, handles connected with the jaws and extending to the rear of the pivot point, biting pieces with tongues engaging in grooves formed in the jaws, and means for holding the biting pieces in place, comprising pivoted levers mounted in the jaws and engag- 65

ing in apertures in the biting pieces, and means for disengaging the levers when the jaws are fully opened, said latter means including pins engageable by the handles, and engaging inclined ends of said levers and 70 slidables in slots in said jaws.

75 In testimony whereof I have affixed my signature.

FREDERICK SCHWEIGERT.
